UNITED STATES PATENT OFFICE

EARL H. GLENDE, OF CHICAGO, ILLINOIS, ASSIGNOR, BY MESNE ASSIGNMENTS, TO
HENRY JAY STEPHENS, OF CHICAGO, ILLINOIS

DISPLAY EASEL

Application filed February 4, 1932. Serial No. 590,858.

This invention pertains to display easels for posters and the like. Posters are typically thin, flexible sheets with a metal binding strip at two opposite ends, the top and the bottom, the sides unbound so that the poster may be rolled for enclosing in a mailing tube.

Many supports have been devised for holding such posters in extended approximately upright position for display, but the requisites of combined efficiency, simplicity, cheapness, lightness and adaptability for mailing with the poster have not always been considered and have seldom been attained.

15 By my invention a novel easel is presented which represents an embodiment of structural features best calculated to attain a combination of all these desirable attributes.

In order that the invention may be readily understood in all its parts and its manner of application in use with a poster, a preferred embodiment is illustrated in the accompanying drawing and hereafter descriptively set forth; it being understood that departure 25 from details given by way of example may well be had within the spirit of the invention as defined by the subjoined claims.

In the drawing,

20 Figs. 1, 2, 3 and 4 illustrate the poster and easel in connection with successive assembling steps;

Figs. 5 and 6 respectively show the stretching and bracing elements in the flat prior to assembly;

25 Figs. 7 and 8 are respectively fragmental views on a larger scale showing the manner of folding the easel elements; and

Fig. 9 is a view illustrating the adaptation of the poster and easel to a mailing tube.

30 Having reference to the embodiment illustrated in the drawing, the reference numeral 11 designates a poster equipped at the upper and lower ends by metallic binding strips 12. A stretcher element designated at 13 comprises a flat strip of material, such as card-

35 board or the like, having a degree of flexibility sufficient to permit it to be bowed slightly as indicated in Fig. 1 for stretching the poster sheet by inserting terminal tongues 13a beneath the folds of the binding strips, after

which the stretcher element 13 is straightened as indicated in Fig. 2, whereby the poster sheet is stretched lengthwise.

The stretcher strip 13 is longitudinally scored as indicated at 13b in Fig. 2 to facilitate the folding of the same along longitudinally extending parallel spaced lines, the space separating which lines may correspond to the width of the tongues 13a. The longitudinal folding results in imparting to the 55 stretcher strip 13 a channel cross section as in indicated in Fig. 3 which very substantially increases the stiffness of the member 13 as will be readily appreciated.

It will be observed that the stretcher member is also provided (Figs. 1, 2 and 5) with slots 13c intermediate its length which extend from adjacent the scored lines to the two sides obliquely downward with reference to the strip axis and on diverging lines; also 70 that when the stretcher strip is folded into channel or U-section (Figs. 3 and 7) these slots become parallel, lying in a common plane oblique to the plane of the poster and the axis of the strip.

75 The bracing element 14 (Figs. 6 and 8) is provided with an upper terminal tongue 14a and is longitudinally scored along a median line as indicated at 14b. The tongue 14a is 80 separated by vertically extending notches 14c from flanking shoulders 14d. The brace strip 14 is foldable along the scored line 14b into channel or V-section (Figs. 4 and 8) whereby there is imparted to it a substantial degree of 85 stiffness.

The stretcher member 13 having been slightly bowed and engaged with the upper and lower ends of the poster sheet (Fig. 1), straightened (Fig. 2) and longitudinally folded into channel section (Fig. 3), and the brace strip having been folded along the line 14b (Fig. 8), the notches 14c of the brace are engaged with the notches 13c of the stretcher (Fig. 4), whereby the brace is interlocked with the stretcher in supporting relation as shown in Fig. 4, each of the members 13 and 14 cooperating by their interlocked relationship to prevent the unfolding 90 of either member. Thus the stretched poster 100

is supported in a slightly inclined but approximately vertical position.

Where the length of the poster is not materially greater than its width, the disassembled stretcher and brace may advantageously be rolled inside the poster and slipped into a mailing tube 15 as indicated in Fig. 9, the easel elements being but slightly folded along their longitudinal scored lines to conform in 10 a measure to the cylindrical space within the rolled poster. However, the stretcher strip may be transversely scored intermediate its length as indicated at 13d (Figs. 2 and 5) which will enable the flat stretcher strip 13 15 to be folded for mailing in a shorter mailing tube than would otherwise be required where the length of the poster materially exceeds its width. This weakened line 13d will obviously not impair the stiffness of the stretcher strip when in use in its channel form as shown in Figs. 3 and 4.

I claim:

1. An easel for flexible posters comprising a stretcher member and a brace member, the former flexible when flat and folded longitudinally into channel section, the ends of the stretcher engaged with the top and bottom of the poster and one end of the brace engaged with angularly disposed walls of the stretcher intermediate its length to maintain the channel section of the stretcher and to support the stretched poster.

2. An easel for flexible posters comprising a flat stretcher strip and a flat brace strip, the stretcher adapted to engage at its two ends the top and bottom of the poster and to be thereafter folded longitudinally into channel section, the brace adapted to be folded longitudinally into channel section and to engage and interlock at one end with the medial portion of the folded stretcher, whereby when the poster and stretcher and brace are assembled the elements are interlocked to maintain the stretched condition of the poster and the folded condition of the stretcher and brace.

3. An easel for flexible marginally-bound posters comprising a flat stretcher strip and a flat brace strip, the stretcher adapted to be bowed and to engage at its two ends beneath the binding at the top and bottom of the poster and to be thereafter folded longitudinally into U-section, the brace adapted to be folded longitudinally into V-section and to engage and interlock at one end with the medial portion of the folded stretcher, whereby when the poster and stretcher and brace are assembled the elements are interlocked to maintain the stretched condition of the poster and the folded condition of the stretcher and brace.

4. In a poster easel a stretcher member comprising a flat strip of flexible characteristics having a length corresponding to that of the poster and having ends for engagement with

the top and bottom of the same, said strip foldable along longitudinally spaced lines into channel section to stiffen the same, and a shorter brace member comprising a flat strip of like characteristics and foldable along a median line into channel section to stiffen the same and having an end adapted when so folded to interlock with the folded stretcher member intermediate the ends of the latter, whereby the sectional shape of said members and their resultant stiffness is maintained.

5. In a poster easel a stretcher member comprising a flat strip of flexible material having a length corresponding to that of the poster and having ends for engagement with the top and bottom of the same, said strip foldable along longitudinally substantially parallel spaced lines into U-section to stiffen the same, and a shorter brace member comprising a flat strip of like characteristics and foldable along a median line into V-section to stiffen the same and having an end adapted when so folded to interlock with the folded stretcher member intermediate the ends of the latter, whereby the sectional shape of said members and their resultant stiffness is maintained.

6. A display easel for posters and the like comprising a flat strip of flexible material having a length substantially the same as the over-all poster height with its ends adapted to engage the top and bottom of the poster, said strip longitudinally scored along parallel spaced lines to facilitate folding into channel section and having intermediate its ends slots extending from adjacent the scored lines to the two sides obliquely downward with reference to the strip axis, and a brace strip of flexible material longitudinally scored along its axis and provided with spaced slots adjacent one end and extending to the end parallel to the strip axis, the brace adapted to be folded into channel section and to have its slots inter-engaged with the slots of the channel stretcher.

7. A display easel for posters and the like having top and bottom binding strips, comprising a flat stretcher strip of flexible material having a length slightly greater than the length of the poster between binding strips and having terminal tongues adapted when bowed to seat within spaces beneath the binding, said stretcher strip scored longitudinally along parallel spaced lines to facilitate folding into U-section after the tongues are seated beneath the binding, said stretcher strip also provided intermediate its length with slots extending from adjacent the scored lines to the two sides on downwardly diverging oblique lines, and a brace strip of similar material longitudinally scored along its axis and provided with spaced parallel slots adjacent and extending to one end, the brace adapted to be folded along its axis into V-section and to have its slots engaged.

with the slots of the stretcher, whereby the sectional shape of the stretcher and brace and their resultant stiffness is maintained.

8. A display easel for posters and the like comprising a flat strip of flexible material having a length substantially the same as the over-all poster height with its ends adapted to engage the top and bottom of the poster, said strip longitudinally scored along parallel spaced lines to facilitate folding into channel section and having intermediate its ends slots extending from adjacent the scored lines to the two sides obliquely downward with reference to the strip axis, and a brace strip of flexible material longitudinally scored along its axis and provided with spaced slots adjacent one end and extending to the end parallel to the strip axis, the brace adapted to be folded into channel section and to have its slots inter-engaged with the slots of the channel stretcher, said stretcher transversely scored intermediate its length to facilitate folding when flat for inclusion with the poster and brace in a mailing tube.
- 25 9. A stretching and supporting easel for flexible posters, comprising a stretcher strip of flat bendable material and a brace strip of similar characteristics, the stretcher adapted to be bowed and to have its ends engaged with the upper and lower ends of the poster and to be straightened to effect stretching of the poster, and thereafter to be folded longitudinally into channel section to stiffen the same, the brace strip engaged at one end with the stretcher whereby to maintain the stretcher in channel section and to support the same with the poster in approximately upright position.
10. A stretching and supporting easel for flexible posters having top and bottom binding, comprising a stretcher strip of flat bendable material and a brace strip of similar characteristics, the stretcher adapted to be bowed and to have its ends engaged with the upper and lower ends of the poster beneath the binding and to be straightened to effect stretching of the poster, and thereafter to be folded longitudinally into channel section to stiffen the same, the brace strip likewise adapted to be folded longitudinally into channel section to stiffen the same and engaged at one end with the stretcher whereby to maintain the stretcher in channel section and to support the same with the poster in approximately upright position.

In testimony whereof I have hereunto subscribed my name.

EARL H. GLENDE.

CERTIFICATE OF CORRECTION.

Patent No. 1,863,594.

June 21, 1932.

EARL H. GLENDE.

It is hereby certified that error appears in the above numbered patent requiring correction as follows: In the grant, line 4 of the testimonial clause, for "fourteenth day of June" read twenty-first day of June; and that the said Letters Patent should be read with this correction therein that the same may conform to the record of the case in the Patent Office.

Signed and sealed this 11th day of February, A. D. 1936.

Leslie Frazer
